UNITED STATES PATENT OFFICE.

JOHN P. WEIS, OF NYACK, NEW YORK, ASSIGNOR TO METROPOLITAN SEWING MACHINE CORPORATION, OF NYACK, NEW YORK, A CORPORATION OF DELAWARE.

WIRE FABRIC AND METHOD OF MAKING THE SAME.

Application filed October 12, 1927. Serial No. 225,632.

This invention relates to wire fabrics, an object of the invention being to provide an improved wire fabric having a friction-grip cushioned edge formed of one or more 5 threads of yarn, string, or similar material, permanently interlaced, braided, knitted, crocheted, or stitched thereto.

A further object of the invention is the provision of an improved wire fabric and 10 method of making the same adapted particularly for use as window and door screening and analogous purposes, having a friction-grip cushioned edge formed of material different from that of which the fabric 15 itself is formed.

A further object of the invention is the provision of an improved wire fabric having at intervals markers to designate the length of the fabric and also to facilitate 20 the cutting thereof at right angles to its length.

A further object of the invention is the provision of an improved wire fabric or cloth provided with reinforced cushioned 25 edges of relatively soft and compressible material, permanently secured to the fabric, and which fabric may also be provided at intervals with markers of similar or different material.

30 This new wire fabric is easy to handle, the composite edge margins form a friction-grip cushioned edge providing a very convenient rib to grasp for stretching the fabric on a frame or the like when securing the screen in place, and also offers great resistance to pressure to prevent sagging when secured to a frame and clamped between two members like those used for doors and windows. This friction cushioned margin facilitates 35 not only the handling during the stretching of it on frames, but also while tacking it in place; and when the usual cover clamping strip is nailed over the friction cushioned edges the stitches tied around the wires of 40 the fabric grip and clamp each wire tightly so as to act similar to the brake lining of an automobile between the two metal surfaces which clamp against the brake lining, since the friction cushioned stitches will be 45 pressed between the frame members to compensate for any irregular nesting of the fabric on the clamp members, whereby the fabric will stay put against greater pressure even though fewer nails be used to secure it 50 in place. Moreover, this friction cushion

edged wire fabric is less apt to cut or injure the worker's fingers. The friction cushioned edges also offer a means of marking the distance to accurately sever the fabric to length, square with the longitudinal edges, 60 and by counting the markings, lineal measurement is determined without a measuring instrument.

Thus among the advantages of the invention may be noted the following: A wire 65 fabric is provided having a friction-grip cushioned and reinforced edge formed of a composite or compound margin along such edge, which is compressible and which cushioned edges may be used to provide markers 70 to indicate the lineal measurement and facilitate the squaring of the fabric during the cutting thereof and to serve as a guide when severing the cloth across its width.

In the drawings accompanying and forming 75 a part of this specification, Fig. 1 illustrates my new wire fabric with friction cushioned edges; Fig. 2 is an enlarged section illustrating how the wire fabric is clamped between frame members; Fig. 3 80 shows one form of marker in the form of braid or tape secured to the fabric; Fig. 4 shows another method of marking by zig-zagging the needles and thereby the stitch toward and from one another simultaneously with the stitching; Fig. 5 shows an overstitched edge which may also be formed or provided with markers; Fig. 6 is an enlargement of a suitable form of stitch. The view shows a stitch around each cross wire 85 of the fabric; Fig. 7 shows the same stitch as Fig. 6 but wrapped around every other wire; and Fig. 8 shows a fabric having another form of marker made up of small circular pieces of material like washers of 90 tough paper or other material, secured to the edges, and in combination this figure shows a thread alternating back and forth cross the fabric from one marker to another, thus forming a straight edge to guide the 95 cutting of the fabric to length.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings, since the invention is capable of 110

other embodiments, and that the phraseology which I employ is for the purpose of description and not of limitation.

The warp wires of the fabric are designated by 2 and the weft or woof or filler wires of the fabric by 1 and these wires may be woven to form any kind of fabric with meshes to suit any needs.

The new feature of this fabric is the friction cushioned edge 3 along each border permanently secured thereto. In the present instance this cushioned edge is shown formed by stitching by means of sewing machines which pass the needles through each or every other mesh, thus carrying the loops of needle thread around the woof wires, the needles coating with loopers which may also carry threads. In this way a two-third stitch is formed making a rib 20 of sufficient size to form a friction cushioned grip.

Other means such as knitting needles either latched or spring needles may be used to form the stitches.

While various forms and kind of stitches may be used the stitches shown in Figs. 1, 2, 3, 4, 6 and 7, are the Grover and Baker, now known as United States Government stitch 401, comprising a needle thread 4 and a looper thread 5. This type of stitch can be formed differently by arranging the tensions of needle and looper threads so as to make tight or loose stitches, elastic or unelastic stitches, flat, beaded or ribbed 35 stitches, and is therefore very suitable for the present purpose. Another advantage of this type of stitch is that it can be made with continuous threads, thus avoiding the use of and the winding of bobbins.

The stitch has the bulk of or more thread on the bottom than on the top side of the fabric, and the formation permits the stitches to shift under pressure between the wires of the fabric. By the use of larger 45 threads or twine different size friction cushions may be built up, and by the use of different colored material, one fabric can be distinguished from another or one manufacturer's product from that of another.

In Fig. 1 the stitch is illustrated as somewhat flattened while in Figs. 6 and 7 the stitch is ribbed or beaded. In Fig. 6 a stitch bight is formed around each wire and when the looper and needle thread are 55 drawn taut, these threads lie tightly against the wires on top and bottom. These enlarged views show the stitches loose for clearness of description. In Fig. 5 an over-stitch is shown. This formation requires 60 more thread and while not as suitable as the other stitch shown could be used in place of the ribbed stitch.

I also provide edge markers simultaneously with the formation of the friction cushioned edges. In Fig. 4, the stitches 65

are placed at intervals out of line away from the edge of the fabric, for use as markers, or as in Fig. 8 washers 7 are stitched at intervals to the fabric, these washers being formed of suitable material, such as paper 70 or the like, every six or twelve inches to mark the lineal distance.

In Fig. 3, the markers are shown in the form of tapes or braids 8, which protrude from the edge so that when the fabric is in 75 roll form a means is provided to determine the lineal content of the roll.

In Fig. 8, it will also be seen that an additional thread 9 is introduced under the marker 7, or in other instances it may be introduced and fastened by the stitch itself at the point of marking. This thread 9 passes from one of the markers 7 to a marker indicated by 10 and then across the fabric at 11 to a marker 12, then along the fabric 13 to 85 a marker 14, then across the fabric 15 to a marker 16, and then along the fabric as at 17 to repeat the alternate line of travel. This combination marker indicates the lineal distance and also provides a straight edge 90 across the fabric so that it may be cut on a straight line without the aid of a square or other instrument. This thread marker is inexpensive and readily withdrawn after it has served its purpose and also offers another 95 means to distinguish different classes of fabrics.

In the manufacture of these wire fabrics suitable instrumentalities may be operated in conjunction with the looms so that the 100 stitches can be placed in the edge margins simultaneously with the formation of the fabric, thereby keeping the cost to a minimum. This however is practical only with certain kinds of wire fabric, principally 105 those made from bronze or copper wire that do not require any subsequent treatment other than perhaps a thin lacquer to maintain a bright finish, and such lacquer will not interfere with the friction cushioned edges. 110

In the manufacture and processing of wire fabric that requires a galvanized finish, the friction cushioned edge must be applied after the galvanizing, for it is quite essential to have the wire fabric absolutely clean and to accomplish this, it must be passed through baths of chemicals and electro cleaners, where it is subject to considerable heat and acids that seriously affect the cushioned edges. Therefore, this particular kind of fabric must have the friction cushioned edges applied thereto as a last step in the process just prior to the final rolling of the material. Therefore, the stitching instrumentalities are operated in conjunction with the processing machine to apply the stitches forming the friction cushioned edges as the material feeds through.

Wire fabrics that require a paint or japan must be treated similar to the galvanized 130

wire fabric and the application of the friction cushioned edges would be precisely the same, that is to say, after all the other operations of cleaning, painting, varnishing, and 5 drying have been completed, the stitches would be applied just prior to the final rolling.

It is to be understood that by describing 10 in detail herein any particular form, structure or arrangement, it is not intended to limit the invention beyond the terms of the several claims or the requirements of the prior art.

Having thus explained the nature of my 15 said invention and described a way of constructing and using the same, although without attempting to set forth all of the forms in which it may be made or all of the modes of its use, I claim:

20 1. A screen fabric formed of metal wire and having a mesh adapting it for use for screening purposes and provided along the parallel side edges thereof with sewing machine stitches forming friction-gripped, 25 cushioned edges adapting the fabric to be effectively gripped and clamped along such edges.

2. A screen fabric formed of metal wire and having a mesh adapting it for use for 30 screening purposes and provided along the parallel side edges thereof with sewing machine stitches of relatively soft, compressible material forming friction-gripped, cushioned edges adapting the fabric to be effectively 35 gripped and clamped along such edges.

3. A screen fabric formed of metal wire and having a mesh adapting it for use for 40 screening purposes and provided along the parallel side edges thereof with looped threads of a material different from that of which the body of the fabric is formed 45 forming friction-gripped, cushioned edges adapting the fabric to be effectively gripped and clamped along such edges.

45 4. A screen fabric formed of metal wire and having a mesh adapting it for use for screening purposes and provided along the parallel side edges thereof with sewing machine stitches passing between and around 50 the woof wires of the fabric forming friction-gripped, cushioned edges adapting the fabric to be effectively gripped and clamped along such edges.

55 5. A screen fabric formed of metal wire and having a mesh adapting it for use for screening purposes and provided along the parallel side edges thereof with sewing machine stitches after the body of the fabric is formed 60 forming friction-gripped, cushioned edges adapting the fabric to be effectively gripped and clamped along such edges.

6. A fabric screen formed of metal wire provided along the parallel side edges thereof with interlocked sewing machine stitches 65 forming friction-gripped, cushioned edges

adapting the fabric to be effectively gripped and clamped along such edges by the frame of the screen.

7. A screen fabric formed of metal wire and having a mesh adapting it for use for 70 screening purposes and provided along the parallel side edges thereof with sewing machine stitches forming friction-gripped, cushioned edges adapting the fabric to be effectively gripped and clamped along such 75 edges, said fabric having markers at predetermined distances along a parallel edge.

8. A screen fabric formed of metal wire and having a mesh adapting it for use for 80 screening purposes and provided along the parallel side edges thereof with sewing machine stitches forming friction-gripped, cushioned edges adapting the fabric to be effectively gripped and clamped along such edges, said fabric having markers of a different material along a parallel edge.

9. A screen fabric formed of metal wire and having a mesh adapting it for use for 90 screening purposes and provided along the parallel side edges thereof with sewing machine stitches forming friction-gripped, cushioned edges adapting the fabric to be effectively gripped and clamped along such edges, said fabric having stitched markers at 95 predetermined distances along a parallel edge.

10. A screen fabric formed of metal wire and having a mesh adapting it for use for screening purposes and provided along the parallel side edges thereof with sewing machine stitches forming friction-gripped, cushioned edges adapting the fabric to be effectively gripped and clamped along such edges, said fabric having means for designating the lineal length of said fabric and 100 for facilitating the cutting of the same square with a longitudinal parallel edge thereof.

11. A screen fabric formed of metal wire and having a mesh adapting it for use for 110 screening purposes and provided along the parallel side edges thereof with sewing machine stitches forming friction-gripped, cushioned edges adapting the fabric to be effectively gripped and clamped along such edges, said fabric having means for designating the lineal length of said fabric and for facilitating the cutting of the same square with a longitudinal parallel edge thereof and comprising a material stitched thereto at 120 intervals along the length of the fabric.

12. The method of making wire fabrics which consists of first forming the fabric of wire having a mesh adapting it for use for screening purposes and then passing through 125 the meshes thereof and around the wires of the fabric along the parallel edges thereof a stitch thread of sufficient size to form along the parallel borders of the fabric friction-gripped, cushioned edges adapting the fabric 130

to be effectively gripped and clamped along such edges.

13. The method of making wire fabrics which consists of first forming the fabric of
5 wire having a mesh adapting it for use for screening purposes and then stitching the fabric along the parallel edges thereof with a relatively soft, compressible thread of sufficient size to form along the parallel borders
10 of the fabric friction-gripped, cushioned edges adapting the fabric to be effectively gripped and clamped along such edges.

14. The method of making wire fabrics which consists of first forming the fabric of

wire having a mesh adapting it for use for 15 screening purposes, then passing through the meshes thereof and around the wires of the fabric along the parallel edges thereof a stitch thread of sufficient size to form along the parallel borders of the fabric friction-gripped, cushioned edges adapting the fabric to be effectively gripped and clamped along such edges, and simultaneously providing the fabric at intervals with suitable markers. 20
